UNITED STATES PATENT OFFICE.

SAMUEL JASPER WATKINS, OF PHILPOT, KENTUCKY.

DESIGN FOR A FRAME FOR STUMP-PULLERS.

SPECIFICATION forming part of Design No. 26,905, dated April 13, 1897.

Application filed November 30, 1896. Serial No. 614,003. Term of patent 3½ years.

To all whom it may concern:

Be it known that I, SAMUEL JASPER WATKINS, a citizen of the United States, and a resident of Philpot, in the county of Daviess and State of Kentucky, have invented and produced a new and original Design for Frames for Stump-Pullers; and I do hereby declare that the following is a full, clear, and exact description of my invention, which will enable others skilled in the art to which it appertains to make and use the same, reference being had to the accompanying drawing, which forms a part of this specification.

My invention relates to a novel design for a frame for a stump-puller; and its object is to give an ornamental appearance to the same, by which it will be rendered more attractive.

The leading feature of the design consists in the new and original configuration given to certain parts comprising the frame, as will be hereinafter specifically described.

In the accompanying drawing the figure represents a perspective view of a frame for a stump-puller constructed according to my design.

In the said drawing the reference-numeral 1 designates two parallel base-beams, having their ends turned or curved upwardly, as shown. Secured to each of these base-pieces 30 are two inclined uprights 2, connected together at their upper ends by a top piece 3, to which said ends are secured. Said top piece is formed with a central hole 4, and is beveled or has its sides curved, as shown. On the 35 inner sides of said uprights, at the top and bottom, are ornamental blocks or moldings 5. Intermediate their ends said uprights are provided with handle-bars 6, having their ends curved downwardly and provided with knobs 40 7 at their extremities.

What I claim is—

The design for the frame of a stump-puller, as herein shown and described.

In testimony that I claim the foregoing as 45 my own I have hereunto affixed my signature in presence of two witnesses.

SAMUEL JASPER WATKINS.
